UNITED STATES PATENT OFFICE.

CHARLES B. HOWD, OF CHICAGO, ILLINOIS.

LACING-FLY FOR CORSETS.

1,222,103.

Specification of Letters Patent. Patented Apr. 10, 1917.

Application filed July 15, 1912. Serial No. 709,354.

To all whom it may concern:

Be it known that I, CHARLES B. HOWD, a citizen of the United States, residing at Chicago, in the county of Cook and State 5 of Illinois, have invented new and useful Improvements in Lacing-Flies for Corsets, of which the following is a specification, reference being had to the accompanying drawings, forming a part thereof.

10 The purpose of this invention is to provide improved construction of garments of the character of corsets or corset waists, consisting in an improved lacing fly and its connections with the garment. It consists of 15 the elements and features of construction as described, as set out in the claims.

In the drawings:

Figure 1 is an elevation of a portion of a garment embodying this invention, showing 20 the same in ordinary laced condition.

Fig. 2 is an elevation of the lacing fly which constitutes the characteristic features of the invention, and a portion of the bellows plait to which the fly is attached on 25 the garment, the sheathing of the fly being partly cut away at one point to disclose the lacing and hook-engaging devices with which it is provided.

Fig. 3 is a section at the line, 3—3, on 30 Fig. 1.

Fig. 4 is a detail plan view of one of the lacing and hook-engaging devices of the fly.

In garments of the class to which this 35 invention is applicable, it is desirable to provide at the center of the front means for lacing the garment from top to bottom, adapted for accommodating it at that point to the form and size of the wearer, as is possible to 40 do by lacing, so as to distribute the accommodation equally at both sides of the vertical center line, and permit the gap covered by the lacing to vary in width throughout its vertical extent as required by the necessity 45 of accommodating the garment to the form, and at the same time to provide for completely opening the garment from top to bottom at a different line from that at which the lacing is provided so that, the lacing 50 having been once properly adjusted, the garment can be removed and re-applied without disturbing the lacing. For effecting this result, there is provided a fly which is laced to one edge of the body of 55 the garment and which is hooked to the corresponding opposite edge of the body

at the line at which the garment is to be opened. This causes the line of hooking to be displaced from the center line by the amount of the distance of the edge 60 of the fly at which the hooking is effected from the center line, or line of crossings, of the lacing, which displacement of the line of separation of the garment from the center line of the front varies obviously according 65 to the extent of the gap crossed by the lacing, which varies, as stated, according to the necessity of accommodating the form of the wearer. The edge of the garment at which the hooking is effected for adapting the garment to its purpose of shaping the vertical lines of the form into flowing curves, is necessarily provided with a comparatively stiff "bone" or stiffening stay, and when the lacing fly is similarly stiffened, there is 70 thus formed at one side of the center line a stiffened area not less than that which is required for two such stiffening stays. For symmetry of the garment there must then be provided at the other side,—that is, in the 75 member of the garment to which the lacing stay is connected by the lacing, and therefore at the opposite side of the lacing from that at which the garment is hooked together,—two stiffening stays occupying an 80 area substantially equal to that of the two first mentioned. When the garment is somewhat widely laced, this is liable to carry the stiffened area so far away from the center line of the front as to reach the point 85 at which the form distinctly and somewhat abruptly curves forward at the sides, and this causes the garment, when drawn to the form of the wearer, to bend somewhat angularly at the outer edges of the outermost of 90 these stiffening stays, in following the form around the sides of the wearer, thus preventing flowing curves and causing the garment to interfere with rather than to assist the presentation of natural graceful outlines. 95 To avoid this defect is one of the purposes of this invention, which is accomplished by constructing the lacing fly without a stiffening stay, thus avoiding the necessity for providing more than one stiffening stay in the 100 corresponding position upon the opposite member of the garment.

The omission of the stiffening stay from the lacing fly, leaving the latter quite flexible, renders it liable to be pulled into a zig-zag form by the stress of its hook connections pulling in one direction and its lacing 110

connections pulling in the opposite direction; and to prevent this distortion of the lacing fly is a second specific purpose of this invention. In connection also with the 5 means for accomplishing the purposes above stated, the lacing fly, which has sometimes heretofore been provided entirely detached from the garment except as attached thereto by the lacing and hooks, is connected to the 10 edge of the garment to which it is also connected by the lacing, by the means of a bellows plait or backing web of sufficient extent to accommodate the widest spread ever required at the lacing, so as to afford a backing 15 for the gap crossed by the lacing, which bellows plait, or backing, serves as a means of permanently connecting the lacing fly with the body of the garment independently of the lacing itself.

20 In the drawings, A,—A¹, are the opposite sides of the front portion of the garment which are connected by the lacing and hooking devices. The side, A, is formed at its edge with a sheath, a, for the stiffening stay, 25 B, to which are secured in a customary manner hooks, C, which protrude at the edge of said side, A, for engagement with any suitable engaging devices which may be provided on the fly. The side, A¹, has its edge 30 reinforced by a cord or very light "bone," D, back of which said side is provided with lacing eyelets, E, and back of the lacing eyelets there is provided in this side, A¹, a sheath, a¹, for a stiffening stay, B¹, corresponding to the stay, B, at the other side. 35 The cord or bone, D, is not to be regarded as a stiffening stay, being merely reinforcement for the edge to assist in holding the eyelets. F is the lacing fly. It is made of 40 flexible fabric and consists substantially of a sheath in which are mounted and secured the hook and lace-engaging fittings, G, each of said fittings comprises an engageable terminal, G¹, which is shown in the form of a 45 loop or eye, adapted for engaging one of the hooks, C, of the side, A, of the garment; (but obviously it is immaterial which of the two engaging members last mentioned has the form of the hook and which has the form of 50 the eye, it being only necessary that they be reciprocally constructed for engagement with each other). The fitting, G, in addition to the terminal, G¹, has at the portion which is inclosed within the sheath afforded 55 by the lacing and fly, an aperture or eye, G², and the fitting is secured to the fly by means of an open eyelet, H, which passes through this aperture, that is, through said aperture and through the fabric of the fly at both 60 sides of the fitting, thereby effecting a secure attachment of the fitting to the fabric, while at the same time forming a reinforced lacing opening entirely through the fly. The fitting, G, has wings, G³, G³, extended in opposite 65 directions from the eyeleted aperture,

the edges of said wings at the side toward the engageable terminal, G¹, being in line adapted to seat them in the fold at the edge of the sheath of the lacing fly, and by being thus positioned, these wings position the fitting for direct protrusion of the terminal, G¹, from the edge of the fly. The fittings, G, are spaced apart along the length of the fly at distances corresponding accurately to the distances between the successive eyelets, E, so that the lacing, K, engaging the eyelets, E, and the eyelets, H, and crossing the space between the lacing fly and the side, A¹, in the usual manner, may be operated in the usual manner to connect the parts and draw them together variably throughout the length of the connected edges as required. It will be noticed that the fittings, G, have the engaging eyelets or loops, G¹, and the apertures, G², in line with each other directly transverse to the edge of the wings, G³, which positions them in line directly transverse to the edge of the lacing fly; and from these relative positions of the two features of the fitting, it results that the pull upon the lacing fly of its hook engagements with the side, A, and the pull of its lacing engagement with the side, A¹, being directly opposed to each other, cannot operate to distort or zig-zag the fly, as would be the case if the lacing and hook connections were not thus directly opposed.

The backing or bellows plait, L, is permanently secured at one edge to the side, A¹, of the garment back of the eyelets, E, and is also secured at the opposite vertical edge to the lacing fly at the edge from which the loops or eyes, G¹, project for engagement with the hooks, C. This backing or bellows plait, therefore, at all times affords a complete backing for not only the widest interval between the lacing fly and the side, A¹, but also for the eyelets in both said parts. This bellows plait may be, if desired, provided with light bones, L¹, extending from top to bottom of said bellows plait so as to prevent it from becoming wrinkled or distorted so as to present an inelegant appearance back of the laced aperture.

I claim:—

1. A lacing fly for corsets comprising a flexible fabric sheath and separate lacing fittings secured therein, each of said fittings comprising an engageable terminal which protrudes from one longitudinal edge of the sheath, and a lacing eye back of the terminal within the sheath, said terminal and eye being in line with each other directly transverse to the edge of the sheath from which the said terminal protrudes.
2. A lacing fly for corsets comprising a flexible fabric sheath and separate lacing fittings secured therein, each of said fittings comprising a terminal which protrudes from one longitudinal edge of the sheath adapted

for engagement to pull the ensheathed part of the fitting to that edge, and oppositely-extended wings back of the protruding terminal engaged with the fold of the sheath
 5 at the edge through which the terminal protrudes, and having also an eye back of the fold-engaging edge of said wings, said eye and the protruding terminal being in line with each other directly transverse to said

10 edge of the wings.

3. A lacing fly fitting consisting of a piece of stiff material adapted to be infolded in a sheath and having a substantially straight edge adapted to be stopped at the fold of such sheath, and comprising a terminal projecting from said edge and adapted to protrude from the fold of an inclosing sheath and to be engaged for pulling said edge into such fold, and a lacing eye at the opposite 15 side of said edge from said terminal in line therewith directly transverse to said edge.

4. A lacing fly fitting comprising a terminal and a lacing eye and straight-edged means by which it is adapted to be engaged 20 with a sheath at a fold thereof with the terminal projecting from the fold and in line with the eye transverse to the fold, said terminal being adapted to be engaged for pulling the fitting into the fold.

5. A lacing fly fitting having an extended substantially straight edge and a terminal projecting from said edge adapted to be engaged for pulling in the direction in which it projects, and a lacing eye directly opposite the terminal back of said edge.

6. A lacing fly fitting comprising two oppositely extending wings having their corresponding edges at one side substantially straight and alined; a terminal projecting transversely to the line of said alined edges intermediate the wings adapted to be engaged for pulling away from said alined

edges, and having directly opposite said terminal a lacing eye adapted to receive an eyelet, whereby such fitting is adapted to be 45 mounted in a flexible sheath comprising a folded edge with which the alined edges of the wings may engage from which the terminal may project when the fitting is secured in such sheath by such eyelet.

7. In combination with a flexible fabric sheath having one edge formed by a fold of the fabric; a lacing fly fitting consisting of a piece of stiff material infolded in the sheath and having a substantially straight edge stopped at the fold thereof, said fitting comprising a terminal projecting from said fold, and a lacing eye at the opposite side of said straight edge in line therewith directly transverse to said edge.

8. A lacing fly comprising, in combination with a flexible fabric strip folded to form one edge of the fly; a fitting consisting of a piece of stiff material comprising two oppositely-extended wings having their corresponding edges at one side substantially straight and alined, said straight edge being engaged in the fold of the fabric and said fitting having a terminal projecting from the line of said alined straight edges intermediate the wings through the fold and adapted to be engaged for pulling away from said alined edges, and having directly opposite said terminal a lacing eye adapted to receive an eyelet; whereby the pull between the terminal and the eye draws said alined straight edges directly into the fold.

In testimony whereof, I have hereunto set my hand at Chicago, Illinois, this 8th day of July 1912.
